UNITED STATES PATENT OFFICE.

FRANK A. LUNDQUIST, OF CHICAGO, ILLINOIS

CALLING DEVICE FOR TELEPHONE-EXCHANGES.

No. 870,634.

Specification of Letters Patent.

Patented Nov. 12, 1907.

Application filed May 28, 1906. Serial No. 319,065.

To all whom it may concern:

Be it known that I, FRANK A. LUNDQUIST, a citizen of the United States of America, and a resident of Chicago, county of Cook, and State of Illinois, have invented certain new and useful Improvements in Calling Devices for Telephone-Exchanges, of which the following is a specification.

My invention relates to calling devices for telephone exchanges, and has for its object improvements in such devices.

In the accompanying drawings Figure 1 is a front elevation; Fig. 2 is a rear elevation; Fig. 3 is a view partly broken away in the direction of the arrow 3 of Fig. 2; Fig. 4 is a section on line 4—4 of Fig. 3; Figs. 5 and 6 are partial views similar to Fig. 3 showing some of the operating parts in different positions. Fig. 7 is a partial section on 7—7 of Fig. 4 at the time of making contact between the part in section and the contact spring it engages; Fig. 8 is a partial section on line 8—8 of Fig. 4; and Fig. 9 is a detached view of the lever by which the device is operated.

In the said drawings A is a dial plate having a series of numbers or characters on a portion A¹ adjacent to one part of its face. In said dial plate is a slot A² having lateral extensions toward the indicating characters A¹, and terminating in a large opening A⁴. Secured to the back of the dial A, by suitable posts, is a clock mechanism B provided with a motor spring B¹, and a governor B² for preventing too rapid movement. A ratchet and pawl mechanism B⁴ serves to cause the governor B² to be driven by the spring B¹ only during the return to normal movement, which movement is that in which the actuating electrical contacts are made by the calling device.

Secured to the center post C, on which the spring B¹ is mounted, is a plate C¹ provided with lips C², between which lips is pivoted an arm or lever D. The arm D normally projects up through the slot A²—A⁴ and its free end terminates in an inclined finger-hold head D¹ which normally rests in the position shown in Figs. 1 and 3. By taking hold of the projecting part D¹ and moving toward the left past the laterally projecting openings A³ the plate C¹ is rotated and the spring B¹ is wound up. By observing Fig. 3 it will be seen that the projecting part D¹, which the operator takes hold of with his finger, is above the pivoting point of the arm D. Pressure on the finger piece D¹ to move it to the left, as shown in Fig. 1, will therefore act to turn the lever D outward on its pivot. Such outward movement is, however, prevented by the lever itself engaging the inner face of the dial A.

Insulatingly secured to the plate C¹ is a toothed sector C³, one portion C⁴ of which is bent downward as shown in Figs. 3 and 7. Insulatingly secured at some convenient part of the framework of the device are two contact springs E and E¹, one of which is adapted

to be engaged by the teeth of the sector C³, and the other by the projection C⁴. Electrically connected to the sector C³ is a spring C⁵, the free end of which engages a piece of insulation D² on the arm D. Secured 60 to the plate C¹ directly back of or beneath the spring C⁵ is an insulated contact point C⁶.

When the finger piece D¹ is above or in front of the dial plate or disk A, the arm D holds the spring C⁵ away from contact with the point C⁶, but when the 65 finger piece is behind the dial, C⁵ and C⁶ are in electrical engagement. The device is provided with three electrical connections, the springs E and E¹ being connected to the two metallic limbs, on an operating circuit, and the contact point C⁶ to a battery wire. When the spring C⁵ is in engagement with the contact point C⁶, each contact between the sector 70 C³ and the spring E sends an impulse from the battery over one line limb and ground return, while a contact between the projection C⁴ and spring E¹ sends an impulse over the other line limb and ground return. When the spring C⁵ is separated from the battery terminal C⁶, contacts with E and E¹ are non-effective. In addition to these there are two springs, 15 and 16, which are held in electrical connection with each other by an arm C⁸ 80 when the mechanism is in its normal position. When the arm D is moved the movement of the spindle C carries the arm C⁸ away and permits the springs 15 and 16 to separate. These springs are in the receiver circuit and the opening of them prevents a battery current reaching the receiver during the operation of the calling device.

The device is intended for the use of subscribers at the local stations of an automatic telephone exchange, and is particularly adapted to calling station numbers 90 consisting of two or more figures. Assuming that the first figure of the number to be called is "7" the subscriber places his finger against the upper projecting part of the lever D adjacent to the inclined plate D¹, and moves the lever around until the lower edge of the inclined part D¹ is over the lateral slot A³ that is opposite the figure "7" on the indicator A¹. By then pressing the lever down the inclined part will pass through this lateral slot and the entire part engaged by the finger (the inclined part D¹ and the extreme upper projecting part of the lever or arm D) will pass behind the dial A so as to be completely out of the reach of the operator. In fact, it is not really necessary to push the inclined part D¹ down through a slot A³ as that result will automatically be accomplished by merely 95 removing the finger from the part D¹. This will be evident from the fact that the finger pressure on the extreme upper end of the lever D necessary to overcome the comparatively strong resistance of the spring B¹, acts to hold the inclined part D¹ outside of the dial 100 plate A, but as soon as that pressure is removed the comparatively weak spring C⁵ serves to move the lever 105

D inward so that the inner edge of the inclined part D¹ will pass into the nearest transverse slot A³. As soon as this occurs, the action of the spring B¹, in returning the moved parts to normal position, brings the inclined part D¹ against the metal forming the boundary of the slot A³ and forces the finger part back of the dial plate irrespective of the operator or the spring C⁵. As soon as the lever D is completely behind the dial plate A the spring C⁶ engages the contact point C⁶ and completes electrical connection from the battery to the sector C⁸. This position is shown in Fig. 5.

The sector C⁸ is so located with respect to the arm or lever D that when the inclined part D¹ passes through a slot A³ having any particular adjacent number, the 15 said sector, in returning to normal position, will make as many electrical connections with the spring E as was indicated by that number. Thus, after D¹ passes down through slot number "7" and the spring C⁶ engages the contact point C⁶, the sector will make seven 20 contacts with spring E to send seven impulses over the line connected thereto.

Immediately after the projection C⁴ makes contact with the spring E¹ the inner edge of the inclined part D¹ comes into contact with an inwardly inclined piece 25 A⁵ which may conveniently be a part of the metal cut out to form the opening A⁴ in the dial plate A. The superior force of the motor spring B¹ over the contact spring C⁵, forces the free end of the lever D up to the incline A⁵ (Fig. 6) until said lever finally rests in normal 30 position as shown in Figs. 1 and 3. The subscriber may then move the lever D to any other number and repeat the operation.

The construction is such that it is very easy to find the proper slot A³ and place the inclined piece D¹ 35 therein. As soon as this is done and the lever released,

the operation is completely automatic and entirely within the device and cannot be interfered with except by the use of some special tool or appliance.

What I claim is:—

1. In a calling device, a series of indicating characters 40 mounted upon a plate, a lever adapted to be moved by hand, means by which upon releasing the lever after being moved by hand to any indication said lever will pass within the device and out of reach of the operator, and means by which upon said lever passing within the device said 45 device will automatically make a series of electrical contacts corresponding in number to the indication to which the lever was moved by hand.

2. The combination with a dial plate provided with numbers and having openings adjacent to its numbers, of a lever adapted to be manually moved to engage any one of said openings, a contact making device arranged to be set by such movement of said lever, and automatically operating means by which upon releasing said lever, it will pass behind said plate so as to be out of the reach of manual operation and said contact maker will make as many contacts as was primarily indicated by the manual operation of said lever. 50

3. The combination with a calling device arranged to make a series of electrical contacts corresponding to a 60 manual operation thereof, of a lever by which the device is set for any desired number of contacts to be made, and automatically operating means by which upon releasing said lever it will pass within the device and remain there during the making of the desired contacts. 65

4. In a calling device, the combination with a plate, and a lever adapted to move in one direction on one side of said plate and in the opposite direction on the other side, of an electrical connection arranged to be closed when the lever is on one side of the plate and to be open when it is 70 on the other side.

Signed at Chicago, Ill., this 26th day of May 1906.
